US00D566083S

(12) United States Design Patent (10) Patent No.: US D566,083 S
Kim et al. (45) Date of Patent: * Apr. 8, 2008

(54) PORTABLE TELEPHONE

(75) Inventors: Hyun-Sook Kim, Seoul (KR);
Yoon-Young Cho, Seoul (KR);
Chang-Hwan Hwang, Seoul (KR)

(73) Assignee: Samsung Electronics Co., Ltd.,
Kyunggi-do (KR)

() Term: 14 Years

(21) Appl. No.: 29/256,894

(22) Filed: Mar. 27, 2006

(51) LOC (8) Cl. 14-03

(52) U.S. Cl. D14/138

(58) Field of Classification Search D14/137,
D14/138, 147, 218, 341-347; 455/90.3,
455/556.1, 556.2, 575.1, 575.3, 575.4; 379/433.01-433.13;
361/814; 348/14.02

(57) CLAIM

The ornamental design for a portable telephone, as shown and described.

DESCRIPTION

FIG. 1 is a bottom front perspective view of a portable telephone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 4 Drawing Sheets
